BOBBIN FOR MINIATURIZED RADIO CORDS

William J. Browner, San Leandro, Calif.

Application December 31, 1957, Serial No. 49,080

Term of patent 14 years

(Cl. D3—19)

Fig. 1.

Fig. 2.

Fig. 3.

Fig. 1 is a top plan view of a bobbin for miniaturized radio cords, showing my new design;

Fig. 2 is a perspective view; and

Fig. 3 is a side elevational view thereof.

The rear and opposite side, not shown, are substantially mirror images of the front and side shown.

The broken line showing of a representative cord in Fig. 1 is for illustrative purposes only.

I claim:

The ornamental design for a bobbin for miniaturized radio cords, as shown and described.
